(57) **CLAIM**

The ornamental design for an electric connector contact element, as shown and described.

DESCRIPTION

FIG. 1 is a front elevational view of an electric connector contact element;

FIG. 2 is a rear elevational view thereof;

FIG. 3 is a right side elevational view thereof;

FIG. 4 is a top plan view thereof;

FIG. 5 is a bottom plan view thereof;

FIG. 6 is a perspective view of the front and right side thereof; and,

FIG. 7 is a perspective view illustrating a state in use thereof wherein the electric connector contact element is coupled with a wire, which is shown in broken lines.

A left side elevational view of the electric connector contact element is omitted because it is presented symmetrical to the right side elevational view of FIG. 3.

The broken lines showing a wire in FIG. 7 are included to illustrate environmental structure only and form no part of the claimed design.
